Patented Oct. 5, 1976

241,762

SNOW THROWER

Darrell W. Hincklin, Burnsville, Minn., assignee to
The Toro Company, Minneapolis, Minn.

Filed Feb. 6, 1975, Ser. No. 547,988

Term of patent 14 years

Int. Cl. D8—05

U.S. CL. D15—12

FIG. 1

FIG. 2

FIG. 3

FIG. 4

FIG. 5

FIG. 6

FIG. 1 is a perspective view of a snow thrower embodying my new design;

FIG. 2 is a left side elevational view thereof on an enlarged scale;

FIG. 3 is a front elevational view thereof on an enlarged scale;

FIG. 4 is a rear elevational view thereof on an enlarged scale;

FIG. 5 is a top plan view thereof on an enlarged scale; and

FIG. 6 is a right side elevational view thereof on an enlarged scale.

I claim:

The ornamental design for a snow thrower, as shown.
